United States Patent Office.

IRA BISBEE, OF RICHMOND, MISSOURI.

Letters Patent No. 72,593, dated December 24, 1867.

IMPROVEMENT IN BALANCES.

The Schedule referred to in these Letters Patent and making part of the same.

TO ALL WHOM IT MAY CONCERN:-

Be it known that I, IRA BISBEE, of Richmond, in the county of Ray, and State of Missouri, have invented a new and useful Improvement in Scales; and I do hereby declare the following to be a full, clear, and exact description of the nature thereof, which will enable others, skilled in the art to which it applies, to fully understand and use the same, reference being had to the accompanying drawings making part of this specification, which represents a side view of the device illustrating my invention.

This invention consists in a scale constructed with a disk or circular plate, mounted at its centre upon a suitable stand, and having receiving-plates or basins suspended at corresponding sides of the disk at proper points, and also having both sides graduated alike, whereby both graduations will register with each other, so that the weight can be viewed by the buyer and seller simultaneously. My invention further consists in having the plate marked with weights of various denominations, viz, troy, apothecaries', and avoirdupois; also for letters, and American and foreign coins of various denominations.

In the drawings, A represents the base or foundation, from which rise two standards, B. On the upper end of these standards is mounted a concentric disk or circular plate, C, by gudgeons or bearings a. This plate is cut away at two sides, as shown at a', so as to allow the swing of the receiving-plates or basins D, which are suspended from arms e, whose inner ends are secured to the plate. I prefer to cut away the portion as shown, although it is not extremely necessary, for this may be dispensed with, and the arms be extended or project farther from the plate, and the basins or plates connected therewith, as shown. The lowest part of the plate has firmly secured to it an equipoise or weight, E, which causes the return of the plate to its normal position, and to act in connection with the graduations on the plate and be the weighing-medium. Each side of the standards B bears the ends of an upright index or pointer, F, which straddles the plate so that it will mark or note the weight on both sides. As a modification of this, the index or pointer may be secured to the plate, and will swing over a stationary dial which may be mounted on the standard or frame, or in any equivalent manner. The plate C has its graduations on both sides of the same. These graduations are of troy, apothecaries', and avoirdupois weights, of letters, and of various coins of American and foreign countries. A pound weight, as shown on one side of the plate, will also be seen on the opposite side, and so with any other weight. The great advantage of this is, that the buyer can see exactly what weight he is getting, whether the seller informs correctly or not, so that the former can be checked by the latter in any attempt to cheat, or state a false amount. It is well known to all that sellers will throw articles on the scale, and the weight thereof and the momentum of the force will cause the index or pointer to sweep or traverse a greater distance than what it would when in a state of rest, and then call out the amount proportionately. I desire to obviate this evil, and so have constructed my device. The straddling-index will allow both sides to be viewed, and as they are graduated to register with each other, it is evident that there will be no difficulty in the buyer observing the full motion of the plate.

When gold or silver is to be weighed, the scale can be made small, although it will work equally well if on a large plan, for if the limit of the scale were one pound troy, and it be desired to weigh two pounds, one basin or receiving-plate can receive a quantity equal to one pound, and when this is weighed it will only be necessary to fill the other basin until the weight of the other is entirely overcome, and the scale be evenly balanced; and so with larger weights, a double quantity is thus weighed.

The equipoise E, at the bottom of the plate, is firmly secured thereto, so that in operating the scale there will be no vibration thereof, as would be the case if it were pivoted or swung on its bearing. Besides this, the weight will act in connection with the graduations and be the weighing-medium, for the further that it be swung from its place of rest, the greater will be the weight it will weigh, and the graduation and equipoise will be adjusted nicely relatively to each other. It will be seen that the standards B will be the indexes or pointers for the lower part of the disk.

The simplicity of the device is apparent. For miners' purposes it will present a great use in overcoming the objections to separate weights, which are apt to be lost or misplaced in transportation, or changing in size or wear.

I have combined the weights and scale, and have no complicated parts liable to break or get out of order or be unnecessarily detached.

Having thus described my invention, what I claim as new, and desire to secure by Letters Patent, is—

1. A scale consisting of the concentric disk C, having graduations on both sides, registering with each other, the equipoise E firmly secured thereto, and the suspended basins or plates D, substantially as represented and described.

2. The disk C, having graduations on both sides, registering with each other, whereby they can be viewed simultaneously, as represented and described.

3. A scale having the following characteristics, viz, graduations for troy, apothecarie's, and avoirdupois weights, for letters, and for American and foreign coins, substantially as represented and described.

The above specification of my improvement in-scales, signed this eighth day of April, 1867.

IRA BISBEE.
